(57) CLAIM

The ornamental design for a golf club head, as shown and described.

DESCRIPTION

FIG. 1 is a front view of a first embodiment of a golf club head in accordance with our new design.

FIG. 2 is a rear view of the first embodiment of a golf club head in accordance with our new design.

FIG. 3 is a left-side view of the first embodiment of a golf club head in accordance with our new design.

FIG. 4 is a right-side view of the first embodiment a golf club head in accordance with of our new design.

FIG. 5 is a top view of the first embodiment of a golf club head in accordance with our new design.

FIG. 6 is a bottom view of the first embodiment a golf club head in accordance with our new design.

FIG. 7 is a first perspective view of the first embodiment of a golf club head in accordance with our new design.

FIG. 8 is a second perspective view of the first embodiment of a golf club head in accordance with our new design.

FIG. 9 is a cross-section view taken along line 9—9 in FIG. 1.

FIG. 10 is a cross-section view taken along line 10—10 in FIG. 3.

FIG. 11 is a front view of a second embodiment of a golf club head in accordance with our new design.

FIG. 12 is a rear view of the second embodiment of a golf club head in accordance with our new design.

FIG. 13 is a left-side view of the second embodiment of a golf club head in accordance with our new design.

FIG. 14 is a right-side view of the second embodiment a golf club head in accordance with of our new design.

FIG. 15 is a top view of the second embodiment of a golf club head in accordance with our new design.

FIG. 16 is a bottom view of the second embodiment a golf club head in accordance with of our new design.

FIG. 17 is a first perspective view of the second embodiment of a golf club head in accordance with our new design.

FIG. 18 is a second perspective view of the second embodiment of a golf club head in accordance with our new design.

FIG. 19 is a cross-section view taken along line 19—19 in FIG. 11.

FIG. 20 is a cross-section view taken along line 20—20 in FIG. 13.

FIG. 21 is a front view of a third embodiment of a golf club head in accordance with our new design.

FIG. 22 is a rear view of the third embodiment of a golf club head in accordance with our new design.

FIG. 23 is a left-side view of the third embodiment of a golf club head in accordance with our new design.

FIG. 24 is a right-side view of the third embodiment a golf club head in accordance with of our new design.

FIG. 25 is a top view of the third embodiment of a golf club head in accordance with our new design.

FIG. 26 is a bottom view of the third embodiment a golf club head in accordance with of our new design.

FIG. 27 is a first perspective view of the third embodiment of a golf club head in accordance with our new design.

FIG. 28 is a second perspective view of the third embodiment of a golf club head in accordance with our new design.

FIG. 29 is a cross-section view taken along line 29—29 in FIG. 21; and,

FIG. 30 is a cross-section view taken along line 30—30 in FIG. 23.
